CLAIM

The ornamental design for a tabletop basketball game, as
shown and described.

DESCRIPTION

FIG. 1 is a front view of a tabletop basketball game shown
in an open configuration;

FIG. 2 is a rear view thereof, shown in an open configuration;

FIG. 3 is a right-side view thereof, shown in an open
configuration;

FIG. 4 is a left-side view thereof, shown in an open
configuration;

FIG. 5 is a top view thereof, shown in an open configuration;

FIG. 6 is a bottom view thereof, shown in an open configuration;

FIG. 7 is a front view thereof, shown in a folded configuration;

FIG. 8 is a rear view thereof, shown in a folded configuration;

FIG. 9 is a right-side view thereof, shown in a folded
configuration;

FIG. 10 is a left-side view thereof, shown in a folded
configuration; and,

FIG. 11 is a top view thereof, shown in a folded configuration.

Broken lines form no part of the claimed design.
